Inventor:

Catherine O'Hara.

UNITED STATES PATENT OFFICE.

CATHERINE O'HARA, OF NEW YORK, N. Y., ASSIGNOR TO THE BUTTERICK PUBLISHING COMPANY, (LIMITED,) OF SAME PLACE.

DESIGN FOR A CHILD'S COSTUME.

SPECIFICATION forming part of Design No. 14,448, dated November 27, 1883.

Application filed September 26, 1883. Term of patent $3\frac{1}{2}$ years.

To all whom it may concern:

Be it known that I, CATHERINE O'HARA, of the city, county, and State of New York, have invented and produced a new and original Design for a Pattern of a Child's Costume, (numbered 8,890;) and I do hereby declare that the engraved prints accompanying this specification convey to any one accustomed to using paper patterns a clear understanding of how a garment made up by the pattern will appear.

The design combines a full drooping blouse-front and a full drooping blouse-back, that are low and square at the neck, above which is

shown the upper part of a plain waist that is 15 high at the neck and buttoned at the back, a side-plaited skirt and coat-sleeves being added.

What I claim as my invention, and desire to secure by Letters Patent, is—

The design for a child's costume, as shown in the engraved prints accompanying this specification.

CATHERINE O'HARA.
